UNITED STATES PATENT OFFICE.

WALTER E. LOWELL, OF NEW YORK, N. Y.

BILGE-PUMP FOR MOTOR-BOATS.

1,269,290.

Specification of Letters Patent. Patented June 11, 1918.

Application filed April 9, 1917. Serial No. 160,728.

To all whom it may concern:

Be it known that I, WALTER E. LOWELL, a citizen of the United States, residing at New York, in the county of New York, 5 State of New York, have invented certain new and useful Improvements in Bilge-Pumps for Motor-Boats; and I do hereby declare the following to be a full, clear, and exact description of the invention, such as 10 will enable others skilled in the art to which it appertains to make and use the same.

This invention relates to new and useful improvements in pumps, and it pertains more particularly to pumps employed for 15 discharging bilge water from the bilge of vessels.

While the present embodiment of my invention is disclosed as a bilge water pump for vessels, my primary object is to provide 20 a pump structure and an operating means therefor which may be used in any connection in which it may be desirable to employ it, and a special object of the invention is to provide a novel mechanism for operating 25 the pump through the conversion of rotary motion to reciprocating motion, which operating means may be used in any connection in which such conversion of motion is desired.

30 An object of the particular embodiment of my invention which is disclosed in this application is to provide a bilge water pump so constructed that it may be directly operated from any revolving part of the propelling mechanism of a vessel.

Another object is to provide a construction facilitating the installation of the pump and an additional object is to provide means by which a plurality of pumps may be operated.

40 A further object of the invention is to provide a bilge water pump which may be operated from the propeller shaft of the vessel.

45 A further object of the invention is to provide adjustable means for supporting the pump to provide for proper positioning thereof.

50 A further object of the invention is to provide novel means for operating the pump.

55 A further object of the invention is to provide means by which a plurality of pumps may be operated.

Referring to the drawings,

55

Figure 1, is a top plan,

Fig. 2, is a sectional view on the line 2—2 of Fig. 1,

Fig. 3, is a side elevational view,

Fig. 4, is an enlarged detail sectional view 60 of the cam member, in its operative position,

Fig. 5, is an enlarged detail sectional view of the cam member in its inoperative position,

Fig. 6, is a top plan of a modified form 65 of the invention; and,

Fig. 7, is an end view partly broken away of the modified form of the invention.

In the preferred form of the invention the tandem type of pump is employed, the cylinders of said pump being designated by the reference character 15 and the pistons thereof being designated by the character 16, said pistons 16 being formed from a single piece of material the center portion 70 17 of which is preferably rectangular and is provided with a pintle or the like projection 18 on which is mounted a roller 19, the purpose of which will be hereinafter set forth.

80

Each of the pump cylinders 15 is provided with a header or chamber 20 and leading into each of said headers or chambers 20 is a pipe 21 which is extended into the bilge of the boat to which the device is attached.

85

These pipes 21 form the intakes of their respective pumping cylinders. Extending from the headers or water chambers 20 in a plane at right angles to the intake pipes 90 21 are discharge pipes 22 which are connected with a common outlet 23 by means of a pipe 24, it being understood that the outlet pipe 23 is adapted to discharge the water from the pipe 24 overboard of the vessel. 95 The pipes 21 and 22 are provided with suitable valves 23' and 24' respectively to permit of the ingress of water to the cylinders from the intake pipes 21 and to prevent the discharge of water through said pipes, and 100 to permit of the discharge of water through the pipes 22 but prevent the ingress of water through said pipes 22. In the drawings, these valves are illustrated as being of the adjustable check valve type.

105

The reference character 25 designates the propeller shaft of the vessel, and secured thereto in spaced relation are a plurality of

2

collars 26 which are adapted to be adjustably secured in their proper position with respect to the longitudinal dimension of said shaft, and as shown in Fig. 2 one side of each of the headers 20 is extended as at 27 to provide a two part bearing, which bearing is adapted to embrace the shaft 25 between the collars 26 for aiding in supporting the pumps. This two part bearing 10 comprises a right angular cutout portion 28 and a plate 29 each of which is provided with a substantially semicircular bearing face and when said plate 29 is secured to the extension 27 of the plates 31 it will be 15 seen that a circular bearing for shaft 25 is formed.

The opposite end of each of the headers is provided with a perforation 32, and passing through said perforations are rods 33 the lower ends of which are rigidly connected to plates 34 by means of which they are suitably secured to the hull of the vessel. When the bearing members have been secured in position around the shaft, the pump 20 cylinders are positioned so that they lie in a horizontal plane, whereupon set screws 35 are screwed up into engagement with the rods 33. From the foregoing it will be seen that the pumps are supported at one side 25 by the propeller shaft 25 and at the other side by the rods 33.

Secured to the shaft 25 in such a manner that it rotates therewith is a cam member 36 which is provided with a cylindrical 30 flange A extending beyond its cam face inwardly thereof and slidably mounted on the propeller shaft 25 for movement toward and away from the member 36 is a cam member 37 which is hollow in form as illustrated and 35 is adapted for movement longitudinally on the shaft to a position where it will receive the flange A of the cam member 36, as shown. The cam member 37 is provided with projecting bolts or the like 38 which pass 40 through openings 39 in the web 40 of the cam member 36 and by this arrangement the cam member 37 is caused to operate with the cam member 36. The longitudinal movement of the cam member 37 is limited owing 45 to the heads 41 of the bolts 38 engaging the web 39 of the cam member 36. The cam member 37 is provided with a hub or slight extension 43 and pivotally secured to said hub are links 44 to which are pivotally secured 50 the links 45 which in turn are pivotally secured to a collar 46 which surrounds the shaft 25 and is secured thereto by means of set screw or the like 47. Slidably mounted on said links 44 and 45 is a collar 48 55 which is adapted to inclose the said links as shown in Fig. 4 to prevent the same from buckling on their pivots 49 as shown in Fig. 5, and pivoted as at 50 is a lever 51 which is provided with forked end 52 by 60 which the collar 48 is moved longitudinally

on the propeller shaft into and out of engagement with said links 44 and 45.

When the parts are in the position shown in Fig. 4, the flange A of the cam member 36 is received within the cam member 37 and the cam faces of the two members provide a continuous cam slot 53 in which the roller 19 carried by the pintle 18 is adapted to operate and it is apparent that upon rotation of the shaft the cam slot 53 causes a 70 reciprocation of the pump pistons 16 within their cylinders 15 thus setting up the pumping operation. If now the parts be moved to the position shown in Fig. 5 it will be seen that the collar 48 is disengaged 75 with the links 44 and 45 and said links are free to rock about their pivots permitting of longitudinal movement along the shaft of the cam member 37. With the parts in this position the cam slot 53 is of such dimension that neither of its walls will engage the roller 19 carried by the pintle 18 and therefore no reciprocation of the pistons 16 is had, what may be termed the "high points" of the two cam surfaces having been 80 brought into planes spaced to an extent greater than the dimension of the roller 19 transversely of the slot.

In the modified form, a twin pump is used, the pistons 16' of which operate in the cylinders 15' and said cylinders 15' are connected by means of a header or the like 20'. Projecting from each of the cylinders 15' is an intake pipe 21' there being an intake pipe 95 for each pump cylinder, and extending from the header 20' is a discharge pipe 21'. The intake pipes 21' are each provided with valves 23', and the outlet pipe 22' is provided with a valve 24' by which the passage of water through the pump cylinders is controlled.

In this form of invention, the pump cylinders are provided with notches 60 in which bearing blocks 61 are supported which latter surround the propeller shaft 25' and the header is provided with a pair of spaced openings or perforations 32' through which the rods 33' extend for the purpose of adjustment, and said cylinders are retained in their adjusted position with respect to 110 the rods by means of the set screws 35'. In this form of the invention each of the pistons 16' is provided with a pintle 18' on which is mounted a roller 19' which is adapted to operate in the cam slot 35 of the two members 36 and 37 which are of the same type as those in the preferred form of the invention.

Having thus described the invention, what is claimed, is:

A bilge water pump support comprising in combination with a propeller shaft, a plurality of vertically extending standards, a plurality of pumping cylinders, bearings carried by the cylinders and embracing the 130

propeller shaft for supporting one side of the pump, said cylinders being provided with means for engaging the vertically extending supports to support the other side 5 of the pump, pistons operating in the cylinders, and means carried by the shaft for operating said pump pistons.

In testimony whereof I affix my signature in the presence of two witnesses.

WALTER E. LOWELL.
